SHEET METAL REEL

Frederick R. Schaefer, Youngstown, Ohio, assignor to Republic Steel Corporation, Cleveland, Ohio, a corporation of New Jersey

Application November 4, 1949, Serial No. 125,464

2 Claims. (Cl. 242—123)

1

This invention relates generally to reels for elongated articles and is particularly concerned with a reel which is constructed of thin sheet metal and yet is suitable for heavy-duty use as, for example, in shipping such things as copper cable, wire, rope and the like.

Heavy, elongated articles, for example, copper cable, were long ago shipped on wooden reels. These reels were not only heavy and short lived, but became more and more expensive as time went on. More recently, efforts have been made to substitute metal reels for such wooden reels, but initially these efforts were embodied in reels of heavy construction which meant that not only was their heavy weight a disadvantage, but that the cost was proportionately high. From time to time efforts have been made to lighten the weight of metal reels and some reels which I have devised heretofore and for which patent applications have been filed have been quite successful commercially.

The present invention aims to provide a heavy-duty, light-weight sheet metal reel which will be lower in cost than many reels now in commercial use and which, despite the fact that thin sheet metal is employed, will possess the necessary strength for satisfactory use with such heavy articles as copper cable.

The present invention will be better understood by those skilled in the art from the following description of the accompanying drawings, in which:

Fig. 1 is an end elevational view of one form of reel embodying the present invention;

Fig. 2 is a fragmentary, cross-sectional view taken on line 2—2 of Fig. 1;

Fig. 3 is a side, elevational view of the hub of the reel of Figs. 1 and 2 before assembly with the reel ends;

Fig. 4 is a fragmentary, end elevational view of one of the end rings of the reel of Figs. 1 and 2; and

Fig. 5 is an elevational view of the reinforcing member of the reel of Fig. 1.

The embodiment of the invention shown in the accompanying drawings comprises a hub 1 and two end assemblies, each consisting of a ring 2, a disk 3, a disk reinforcing member 4 and means 5 for securing the end assemblies to the hub.

The hub 1 is composed of thin sheet metal which is rolled into a cylinder 9 with its ends fastened in any suitable way, as by welding, to a metal strip 10. Ears 11 project from each end of the cylinder 9 at circumferentially spaced

2

places and near their ends are perforated as at 12.

As just stated, each end assembly includes a ring 2, a disk 3 and a reinforcing member 4 with securing means 5. A description of one such end will suffice for both ends of the reel.

Each ring 2 comprises a body portion 15 through which extend perforations 16 at places spaced circumferentially corresponding to the spacing of ears 11 of the hub. The body portion is substantially perpendicular to the axis of the hub and the inner portion of the ring is bent outwardly to form a flange 17 extending coaxially with the hub and lying against the inner surface thereof. The inner edge portion of the ring at the end of flange 17 is bent inwardly and is perforated as at 18. When the ring 2 is assembled with hub 1 and the perforated end portions of ears 11 are bent inwardly, the perforations 12 in these ears and 18 in the ring are in alignment so that securing means may be passed therethrough.

Each disk comprises a body portion 20 provided with an inturned flange 21 defining an opening 22 to receive a bar on which the reel may be mounted for rotation during the coiling of an elongated article on the reel or uncoiling it from the reel. The disk is also provided with two other annular flanges 23 defining holes 24 on opposite sides of the central hole 22. These flanges 21 and 23 seat in and closely engage the inside surfaces of holes in member 4 which extends diametrically of the hub 1 and serves to strengthen and increase the rigidity of the disk within the end of the hub.

The body 20 of disk 3 is provided with small depressions 25 spaced circumferentially apart to correspond with the location of ears 11 of the hub 1. These depressions 25 are perforated and the perforations may be aligned with perforations 18 of ring 2 and perforations 12 of hub 1. When these three parts are assembled as shown in Fig. 2, securing means 5, such as screws, may extend through the said perforations and hold the three parts in assembled position.

The body portion 20 of disk 3 is perpendicular to the centerline of the hub 1 from the center outwardly to a point radially well beyond the outer surface of hub 1. There the disk 3 is bent inwardly toward ring 2 to form a circumferential groove-like depression 27, the bottom 28 of which has holes 29 extending therethrough at diametrically opposite points and, at circumferentially spaced places, this bottom wall 28 is further depressed, as at 30, to engage the ring 2 to which the disk may be secured, as by welding.

The outer edge portion of ring 2 is bent to form a flange 35 which extends axially of the reel and lies in contact with the outer surfaces of the part 36 of disk 3 which defines the radially outer side of depression 27. Prolongations 5 of flanges 35 and 36 are brought into contact with each other and are then bent radially outward, then axially inward of the reel and then axially outward again and are thus rolled and folded together so as to form a rim composed of 10 five layers of metal, each pressed into contact with the layers on opposite sides thereof and all the layers together forming a rim of considerable resistance to deformation. Preferably this rim is provided with a circumferential depression 37 with which a driving or braking belt may be assembled.

From the accompanying drawings and the foregoing description, it will be seen that the reel there illustrated is composed of thin gauge sheet metal parts and that these parts are so devised, assembled and connected together that they give the reel a high degree of strength. The metal constituting the disk was 20 gauge and that 20 constituting the ring and drum and reinforcing members 25 was 18 gauge.

In contrast with the wooden reels of the prior art, reels embodying the present invention have a constant weight, i. e., the weight does not change due to absorption or loss of water as occurs with wooden reels; do not splinter when dropped with formation of slivers which often penetrate insulation on cable on the reel and make it unusable; and, on the basis of capacity, cost only about one-third as much to produce. In 30 contrast with metal reels of the prior art, reels embodying this invention weigh less than, and cost about one-third as much as, the prior metal reels of the same capacity.

Having thus described the present invention so that others skilled in the art may be able to understand and practice the same, I state that what I desire to secure by Letters Patent is defined in what is claimed.

What is claimed is:

1. A heavy-duty, light-weight metal reel, suitable for carrying cable and the like, comprising a cylindrical sheet metal hub and reel ends attached thereto, said hub having circumferentially spaced ears extending from its ends and bent radially inward near their ends, each of said reel ends including a sheet metal ring and a disk, said ring having a body portion perforated for said

ears to extend through and being bent axially outward to bear against the inner surface of said ears and having an inwardly extending flange at its inner edge, said disk having a body portion indented at circumferentially spaced points to bear against said inwardly extending ears, means securing said disk, ring and ears in assembled position, the outer portions of said ring and disk being connected to form a rim.

2. A heavy-duty, light-weight metal reel, suitable for carrying cable and the like, comprising a cylindrical sheet metal hub and reel ends attached thereto, said hub having circumferentially spaced ears extending from the ends of the hub and bent radially inward and perforated near their ends and reel ends attached to said hub, each of said ends including a sheet metal ring, and a disk, said ring having a body portion perforated for said ears to extend through and being bent axially outward to bear against the inner surface of said ears and having an inwardly extending flange at its inner edge perforated to align with the perforations in said ears, said disk having a body portion indented at circumferentially spaced points to bear against said inwardly extending ears and having perforations to align with the perforations in said ears and ring, screws extending through the aligned perforations in said disk, ring and ears for securing these parts in assembled position, the outer portions of said ring and disk being connected to form a rim.

FREDERICK R. SCHAEFER.
